UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PULL-SWITCH SOCKET.

1,102,639.

Specification of Letters Patent.

Patented July 7, 1914.

Application filed November 3, 1910. Serial No. 590,501.

To all whom it may concern:
Be it known that I, REUBEN B. BENJAMIN, a citizen of the United States, residing at Chicago, in the county of Cook and State 5 of Illinois, have invented new and useful Improvements in Pull-Switch Sockets, of which the following is a full, clear, concise, and exact description, reference being had to the accompanying drawing, forming a 10 part of this specification.

This invention relates to improvements in switch sockets for electric lamps, and particularly to that type of switch socket in which the switch is opened or closed, to 15 extinguish or light the lamp, by pulling upon a chain, cord or the like. As sockets of this class are usually constructed, if a shade be used the operating chain or cord extends over the edge of the shade and 20 from this point hangs down to where it can be reached by a person desiring to manipulate the switch. When the chain or cord is pulled upon, the fixture, because of the fact that the chain hangs from a point consider- 25 ably removed from the center of the device, is jarred or caused to oscillate to such an extent as to endanger the filament of the lamp, especially if the latter be a tungsten or tantalum filament lamp, which as is well known, 30 are not adapted to withstand rough usage.

It is one of the objects of my invention to provide a device in which the possibility of the fixture being jarred or caused to oscillate is greatly reduced, so that the danger 35 of the filament of the lamp being destroyed is made much smaller than with lamp-holding devices as heretofore constructed.

Another object of the invention is to so attach the shade to the socket that if the 40 former be accidentally struck it may tilt to some extent, whereby the transmission of a destructive jar to the socket and the lamp carried thereby is prevented.

In the accompanying drawings, in which I 45 have illustrated embodiments of my invention, Figure 1 is a longitudinal sectional view of a socket carrying a shade and lamp, this socket being provided with switch mechanism operated by the means which 50 I have invented; Fig. 2 is a cross sectional view of the same on the line 2—2 of Fig. 1 looking upward; Fig. 3 is a cross sectional view of the same on the line 3—3 of Fig. 1 looking downward; Fig. 4 is a

partial cross sectional view on the line 4—4 of Fig. 1 looking downward; Fig. 4 is a perspective view of the upper end of a tape which I employ in the construction illustrated in Figs. 1 to 4 inclusive; Fig. 6 is a partial longitudinal sectional view of a 60 modified socket and shade employing some of the features of my invention; Fig. 7 is a top plan view of this form of the device; Fig. 8 shows a cross section on the line 8—8 of Fig. 6 looking downward; and Fig. 9 65 shows a cross section on the line 9—9 of Fig. 6, looking downward.

Referring first to Figs. 1 to 5 inclusive, 10 is a tubular casing shell formed of sheet metal or other suitable material and having 70 its upper end drawn in at 11 to form a tapering or cone-shaped neck through which enter the feed wires. The lower end of the casing shell 10 has screw threads 12 rolled thereon, the extreme lower edge 13 being 75 flanged outwardly to form a ledge or shelf which supports a shade holder 14, the upper edge of which is flanged inwardly at 15 and rests upon the ledge 13. The shade holder 14 is of suitable size at its mouth 16 to receive the upper edge or neck 17 of a shade of the size commonly employed with metal filament lamps, or may be made to receive any size shade desired. Suitable means, such as the screws 18, are employed for holding the shade in place in the shade holder. A threaded ring 19 screws up into the lower end of the casing shell 10 and has its upper edge 20 flanged inwardly to support a ring-shaped member 21 formed of insulating material, preferably porcelain. Within the ring-shaped member 21 is a threaded metallic sleeve 22 adapted for the reception of the base 23 of the lamp 24. This threaded sleeve 22 is prevented from dropping out of 90 the ring 21 by having its upper edge 25 flanged over upon a suitable shoulder formed on the ring 21, and is prevented from passing upward out of the ring 21 by having its lower edge 26 flanged outwardly beneath a shoulder suitably formed on the ring 21. To prevent rotation of the sleeve 22 in the ring 21 when the lamp is 95 screwed into or out of the sleeve a lug or projection 27 is provided on the porcelain 100 ring 21 which extends into a corresponding notch in the outwardly flanged edge 25 of the sleeve. Resting upon the insulating ring 105

21 is a base 28 which is formed of porcelain or the like and is suitably chambered out to accommodate the mechanism of the switch. The lower side of this base 28 is seen in Fig. 5. 2. A center contact plate 29, for engagement with the center terminal of the lamp, is secured to the under side of the base 28 by means of a screw 30, this screw also holding in place, in contact with the center contact member, a curved strip of spring metal 31, the free end of which extends over into the switch chamber 32. Rotatably mounted upon a shaft 33, which is non-rotatably fixed in the chamber 32 and extends thereacross, is a switch-operating star-wheel 34. This member has six points or fingers, alternate fingers being made long enough to engage the resilient strip 31 and the other fingers being slightly too short to reach this strip. Fulcrumed loosely upon the shaft 33 is a lever 35, a spring 36, which is coiled around the shaft 33 and secured thereto, tending to throw the free end of this lever up. The lever 35 carries a spring tongue or pawl 37 which, when the lever is moved downward, engages one of the fingers of the star-wheel 34 whereby the latter is moved through one-sixth of a revolution upon each movement of the lever 35. A resilient strip 36^a forms the other switch blade member and is arranged so that if permitted it will move into engagement with the free end of the resilient strip 31 and make electrical connection therewith. This strip is secured by means of a rivet 37^a to a conducting strip 38 which leads to a screw 39, the latter extending down through the base to the under side thereof and holding in place a binding plate 40 carrying a binding screw 41. A passage 42 extends through the base through which the feed wire may extend to the binding screw 41. The spring strip 36^a is long enough to be engaged by the short as well as the long fingers of the star-wheel. A second passage 43 accommodates the other feed wire, which extends to a binding screw 44 carried by a binding plate 45. This plate is held in position by a screw 46 which also holds in place a resilient conducting strip or plate 47 which is bent downward and engages with the outward flange 25 on the threaded lamp-receiving sleeve 22 when the insulating ring 21 is in position in the casing 10. It will be seen that when strips 31 and 36^a of the switch mechanism are in contact with each other the circuit will be closed through the lamp, this circuit being traced as follows: from the lead wire which extends down through the passage 42 to the binding screw 41, through the binding plate 40 to the screw 39, thence through conducting plate 38 to the strip 36^a, thence through strip 31 to the center contact 29, thence through the lamp to the threaded lamp-receiving sleeve

22 and plate 47 to terminal plate 45, thence to binding screw 44 and the feed wire which goes out through passage 43. The means for opening and closing the circuit, by separating the plates 31 and 36^a or permitting the same to come together, will now be more fully described. Secured to the outer end of the lever 35 is a thin, partly flexible member 48, which may conveniently consist of a strip of metallic tape. The upper end 75 of this strip is shown, on an enlarged scale, in Fig. 5. A slit 49 is formed in the upper end of this tape in which the notched end of the lever 35 is hooked to retain the tape thereon. This tape extends down through a groove 50 formed in the side of the porcelain ring 21 and emerges from the casing 10 of the socket between the lower edge of the ring 19 and the base of the lamp. As lamps and shades are ordinarily constructed there is but little available space between the base of the lamp and the neck of the shade, but when a thin metallic tape is used for the member which transmits the pull to the movable element of the switch this space is sufficient to accommodate the same. At the lower end of the tape 48, which terminates just below the neck of the shade, a chain 51 is secured, this chain being of any desired length and carrying at its lower end an acorn, ball or other suitable device 52 which may be easily grasped by the hand. In Fig. 1 the switch is shown with the parts in the positions which they will occupy just before the circuit closes, or in other words, with the lever 35 moving downward and the strip 36^a about to be released. When the end of this strip slips off the short finger of the star-wheel it will spring down into contact with the strip 31, thus closing the circuit and lighting the lamp. The chain being released the lever will be thrown up by the spring 36, the spring pawl 37 riding over the next finger of the star wheel and catching in the notch between the same and the succeeding finger. If the chain be again pulled down the pawl 37 engages the long finger and again moves the star wheel through one-sixth of a revolution. During the first part of this movement both of the spring strips 31 and 36^a are raised by a long finger of the star-wheel but remain in contact with each other. Before the lever has reached the limit of its downward travel the spring 31 is permitted to drop off the point of the finger, the spring 36 being still retained by the tooth. This opens the circuit very quickly. During the rest of the movement of the star-wheel on this pull the spring strip 36^a is simply raised. Upon the next pull the strip 36^a is first dropped upon the short finger, to the position shown in Fig. 1, and is then dropped upon the other strip as described above. The upper portion of the chamber in the base which contains the 130

switch mechanism is closed by an insulating disk 53 having a central opening for the passage of the feed wires. Directly over this disk, and extending up into the cone-shaped neck 11 of the casing, is a cone-shaped clamping ring 54 which is formed of insulating material and is split transversely. Springs 55 tend to separate the parts of this ring, but when the supporting ring 19 is screwed up into the lower end of the casing shell so as to force the insulating base of the device up into position the parts of the clamping ring 54 are forced together by the inclined walls of the tapering neck 11. The upper portion of the clamping ring is formed, on the inside thereof, with a wedge-shaped rib 56 which, when the ring closes together upon the conductors, bites into the insulating covering thereof and firmly holds the wires against being pulled through the ring. In this way the binding terminals are relieved of strain.

It will be seen that the binding posts are located on the under side of the base which carries the same and the switch mechanism, and are accessible through the front of the socket when the lamp, threaded ring 19 and insulating ring 21 are removed. There is therefore no necessity for providing any opening or joint anywhere in the casing of the device, as is usual where the casing must be separated into two parts when access is to be had to the binding posts. It will also be observed that there is no opening for the operating cord, chain or tape to work through as is usual with devices of this class. The absence of such openings or joints renders the device more sightly and precludes the entrance of moisture when the device is used in exposed positions. The shade-holding ring 14, by being arranged or adapted to rest loosely upon the outturned edge 13 of the casing shell 10, instead of being rigidly secured thereto as is usual, permits the shade and holder to have a certain amount of angular or rocking movement with respect to the socket. If the shade be accidentally struck the shade and holder, by reason of this loose connection, are permitted to tip and any shock or jar which would be likely to shatter the delicate filament of the lamp is prevented from being transmitted to the filament.

In the form of the device shown in Figs. 6 to 9 inclusive, the insulating base 57 is held up in place in the casing 58 by means of a threaded ring 59 and is chambered out in its under side to accommodate the threaded ring or lamp-receiving sleeve 60. In the upper portion of the casing is arranged switch mechanism of any suitable type which is adapted to be operated by means of a cord or chain. This mechanism is not illustrated in detail as any of the well known forms of pull-operated switches now in use

may be employed. The casing is provided with an opening 61 in which is secured one end 62 of a tubular member 63 which bends downward and through which extends an operating chain 64. In this instance the chain does not pass down within the body of the casing of the socket but is led down through the tubular member 63 and thus made to emerge within the shade 65. The shade-holder 66 is provided with an opening through which the tubular member 63 extends, the shade-holder being in this case rigidly secured to the casing 58. In this form of the device, as in the first-described form, the operating chain extends through the shade, but in this modification a special form of shade is provided, having a groove 67 formed on the inside of the neck thereof. This groove is necessary because of the fact that the chain comes down through the shade at a considerable distance from the center thereof. In this form of the device, as in the other form, the insulating base and parts carried thereby are inserted into the casing from the lower end of the latter and are held up in place therein by a threaded ring attached to the casing.

The socket shown in Figs. 6-9 is intended to be secured to a conduit or the like, instead of being supported from the conductors, as is the case in the construction shown in Figs. 1-5. The means for supporting the socket consists of a bushing 68 (Figs. 6 and 7) formed, at its lower end with a flange 68^a, and having secured thereto, beneath the flange 68^a a ring 70, the ring 70 being held in place by means of a turned-over neck 69 with which the lower end of the bushing 68 is provided. The upper end of the casing is formed with an opening of a diameter which is somewhat smaller than the diameter of the ring 70, so that the casing rim 58^a will rest upon the edge of the ring 70. The casing 58 is secured to the bushing 68 by means of a stepped ring 72, secured to the ring 70 by means of screws 71. It will be seen that when the screws 71 are tightened, the casing rim 58^a is clamped between the rings 70 and 71, and the casing is thus firmly secured to the bushing 68. If, for any reason, it is desired to change the angular position of the casing with respect to the bushing, this may be accomplished by loosening the screws 71 and turning the casing with respect to the bushing until it reaches the required position, whereupon the screws 71 are again tightened to clamp the casing in the new position. By this means, it is possible to locate the switch operating member 64 in any desired angular position, regardless of the position of the bushing 68 when the latter is secured to the conduit.

What I claim as new, and desire to secure by Letters Patent, is:

1. In combination, a lamp socket, a shade

- carried thereby, a switch associated with said socket, and a switch-operating member connected with said switch and passing through the upper part of said shade to a position between the shade and the lamp, whereby vibration of the socket, due to pressure by the switch-operating member on the outer part of the shade, is avoided.
2. In combination, a lamp socket, a shade carried thereby, a pull-operated switch mounted in said socket, an operating member connected at its upper end with said switch, and means for guiding said operating member past the mouth of said shade so that said operating member is disposed between said shade and the lamp carried by the socket, whereby vibration of the socket, due to pressure of the switch-operating member on the outer part of the shade, is avoided.
3. A switch lamp socket comprising an insulating base, lamp contacts associated with said base, a pull-operated switch carried by said base, a casing surrounding said base, lamp contacts, and switch, and an operating member for said switch disposed between said lamp contacts and the casing, for the purposes set forth.
4. A switch lamp socket comprising an insulating base, lamp contacts carried by said base, a pull-operated switch associated with said contacts, a casing surrounding said base and switch and a switch operating member connected to said switch and extending downward and out through the end of said casing, said member being disposed between said base and the casing.
5. In combination, a pair of lamp contacts, a support therefor, a switch associated with said contacts, a casing surrounding said

support and said switch, and having an opening through which a lamp may be inserted to make connection with said contacts, and an operating member for said switch, said operating member being partly inclosed in said casing and extending outward through the opening of said casing.

6. A switch lamp socket comprising an insulating base, lamp contacts carried by said base, a pull-operated switch associated with said contacts, a casing surrounding said base, lamp contacts, and switch, and a flat strip connected to said switch to operate the same, said strip being disposed between said lamp contacts and the casing, for the purposes set forth.

7. A switch lamp socket comprising a center-lamp-terminal engaging contact, a threaded outer-lamp-terminal engaging contact, means for supporting said contacts, a pull-operated switch associated with said contacts, a casing surrounding said contacts, supporting means and switch, and an operating member for said switch, said operating member being connected with said switch and passing through the space between said threaded contact and said casing to emerge at the opening of said casing, said operating member being of small thickness in order to permit it to pass through said space, for the purposes set forth.

In witness whereof, I have hereunto subscribed my name in the presence of two witnesses.

REUBEN B. BENJAMIN.
